US00D861728S

(12) **United States Design Patent** (10) Patent No.: **US D861,728 S**
(45) Date of Patent: ** Oct. 1, 2019

(54) **DISPLAY SCREEN OR PORTION THEREOF
WITH AN ICON**

(71) Applicant: **Siemens Aktiengesellschaft**, Munich (DE)

(72) Inventors: **Philemon Göttle**, Nuremberg (DE); **Jessica Scheiderer**, Nuremberg (DE); **Viola Wolfermann**, Nuremberg (DE)

(73) Assignee: **Siemens Aktiengesellschaft**, Munich (DE)

(**) Term: **15 Years**

(21) Appl. No.: **29/660,964**

(22) Filed: **Aug. 23, 2018**

Related U.S. Application Data

(62) Division of application No. 29/599,880, filed on Apr. 7, 2017, now Pat. No. Des. 841,053.

(30) **Foreign Application Priority Data**

Oct. 7, 2016 (EM) 001453807

(51) LOC (12) Cl. **14-04**

(52) U.S. Cl.

USPC **D14/492**; D14/495

(57) **CLAIM**

The ornamental design for a display screen or portion thereof with an icon, as shown and described.

DESCRIPTION

The FIGURE is a front view of a display screen or portion thereof with an icon showing our new design.

In the FIGURE, the broken lines are for the purpose of illustrating a display screen or a portion thereof and form no part of the claimed design.

1 Claim, 1 Drawing Sheet
